UNITED STATES PATENT OFFICE.

JOHN KERKHOFF, OF CINCINNATI, OHIO.

REVERSING MECHANISM.

SPECIFICATION forming part of Letters Patent No. 653,811, dated July 17, 1900.

Application filed February 28, 1900. Serial No. 6,792. (No model.)

To all whom it may concern:

Be it known that I, JOHN KERKHOFF, a citizen of the United States, and a resident of Cincinnati, in the county of Hamilton and 5 State of Ohio, have invented an Improvement in Reversing Mechanism for Washing-Machines; and I do hereby declare that the following is a full and exact description thereof, reference being had to the accompanying 10 drawings, making part of this specification.

My invention relates to reversing mechanism for washing-machines; and it has for its object the improvement in the construction of such machines whereby they are simplified 15 and rendered more efficient in action.

The novelty of my invention consists in the combination and subcombination of the parts, as will be hereinafter set forth, and specifically pointed out in the claim.

20 In the accompanying drawings, Figure 1 is a side elevation of a reversing mechanism, showing the washer-tub in section. Fig. 2 is an end view of a reversing mechanism, showing part of the bracket broken away. Fig. 3 25 is a rear view of locking device for belt-shifter.

Similar letters of reference indicate like parts throughout the several views of the drawings.

30 The shaft A has all the moving parts of my reversing mechanism attached to it, except the gear B, the gear B being keyed to the trunnion C. The trunnion C, being secured to the cylinder D, revolves in a suitable bearing, which is attached to the head of the tub E. When the gear B revolves, it causes the cylinder D to revolve, motion being transmitted from gear B to cylinder D through the trunnion C. The pinion F is keyed to the 35 shaft A. The pulleys G and H run loosely on the shaft A. The pulley I is rigidly attached to the shaft A with a set-screw, so that when shaft A revolves pulley I revolves also.

The pulley H has a thread or worm J attached to the outer end of its hub, and the worm J, attached to the hub of pulley H, meshes with a worm-gear K. On the face of worm-gear K is a cam L, which works in the opening M at the lower end of the arm N. 45 The arm N is pivoted at about the central point between the cam L and a pin O, projecting in from the top of arm N. The arm N is

pivoted to the projecting arm P of the adjustable bracket Q. The worm-gear K has a hub R, which revolves in a bearing S, the bearing S being part of the arm T, which extends down from the adjustable bracket Q. The worm-gear K is held in position by a cap-screw U, which screws into the hub R of the worm-gear K.

The upper part of the adjustable bracket Q has a projection V, to which the rest v is attached. The head v², which carries the belt-shifter, slides on the rest v. Passing through the head v² is a semicircular piece of iron v³, 65 to which the belt-shifter loops v⁴ are attached. The head v² is attached at its upper part to the end of slidable rod b. The slidable rod b passes through the boss b² at the top of the adjustable bracket Q. Attached to the rod b 70 is a dog b³. At the outer end of the rod b there is a weight or handle b⁴ for throwing the reversing mechanism in gear or out of gear.

To support the outer end of shaft A and form a bearing for the bracket Q, there is provided a bracket e.

The operation of my reversing mechanism is as follows: Two belts, a cross-belt and a straight belt, are used to operate this reversing mechanism. There would be a cross-belt on 80 pulley G and a straight belt on pulley H. The belt on pulley H would revolve the pulley H, and as the worm J is a part of the hub of pulley H the worm J would revolve also. As the worm-gear K meshes with worm J, it would 85 revolve, causing the cam L to revolve with it, and as the cam L revolves in the space M of the arm N it would cause the lower part of arm N to oscillate back and forth, and as the arm N is pivoted to P at about its central 90 point the upper part of arm N describes the arc of a circle of about the same size as the lower part of the arm N did. When the dog b³ is turned over, so that the slot b⁵ catches on the pin O, it causes the rod b to slide back 95 and forth, and as the belt-shifter v³ is attached to the rod b it causes the belts to alternately shift onto the tight pulley I, revolving the cylinder D two or three revolutions in one direction, and then reversing and revolving two 100 or three revolutions in the opposite direction.

When it is desired to stop the machine from working, the dog b³ is turned back into the space b⁶, in which position it holds the belts

on the two loose pulleys, and not being connected with the arm N there will be no shifting of the belts, so that the cylinder D will remain stationary.

5 Having thus described my invention, what I claim as new, and desire to secure by Letters Patent, is—

The combination in a washing-machine reversing mechanism, of two loose pulleys, and 10 one tight pulley, one of the loose pulleys having a worm attached to the outer end of its hub, which meshes with a worm-gear, the worm-gear having a cam projecting from one side that works in an opening at the lower 15 end of a vertical arm, the vertical arm being pivoted at its center to a bracket, the upper end of the vertical arm having a pin project-

ing in from the top to engage with a slot which is in the lower side of a dog, the dog being secured to a rod; this rod having attached to 20 it at one end a head, this head having a belt-shifter projecting laterally and downward from it, each end of the belt-shifter being provided with belt-loops to engage belts, a weight secured at the opposite end of the above- 25 named rod, a pinion on the same shaft with the tight and loose pulleys, this pinion meshing with a gear that is secured to the cylinder of the washer, substantially as described.

JOHN KERKHOFF.
